UNITED STATES PATENT OFFICE.

WILLIAM L. BOYD, OF HAYDEN, ARIZONA.

SMOKE-PURIFIER.

Specification of Letters Patent. Patented Apr. 16, 1918.

1,263,197.

Application filed May 12, 1917. Serial No. 168,182.

To all whom it may concern:

Be it known that I, WILLIAM L. BOYD, a citizen of the United States, and resident of Hayden, in the county of Gila and State of Arizona, have invented certain new and useful Improvements in Smoke-Purifiers, of which the following is a specification.

This invention relates to new and useful improvements in smoke purifiers, and the primary object of the invention is to provide a device of this character through which the smoke is forced to purify the same, and remove therefrom the solid products of combustion, which are adapted to be used for various purposes, and which were heretofore carried off by the waste gases.

This invention particularly relates to a novel apparatus for purifying smoke which comprises a novel arrangement for forcing smoke through a body of water and agitating the body of water to break up and destroy the globules of smoke and gases passing therethrough to insure the separation of the minute solid particles or products of combustion from the globules formed of gaseous particles and secure the precipitation of the solid particles in the body of water and prevent their escape with the gaseous products. The apparatus is furthermore provided with means for withdrawing the precipitation of these solid particles, so that they are adapted to be used for various purposes as desired.

A further object of the invention is to provide a smoke purifying apparatus of this character which includes a liquid containing portion having the purifying apparatus contained therein, and means for maintaining a predetermined liquid level in said portion during the operation of the apparatus.

Still another object of the invention is to provide a device of this character that includes a liquid container provided with means for precipitating the solid products of combustion in the bottom thereof as the smoke passes therethrough, and an overflow whereby the said products are carried from the container to any desired place.

Another object of the invention is to provide a device of this character which is easily and simply constructed, inexpensive to manufacture, and one which will be very efficient in operation.

With these and numerous other objects in view my invention consists of the novel features of construction, combination and ar-

rangement of parts which will be herein referred to and more particularly pointed out in the specification and claims.

In the accompanying drawings: 66

Figure 1 is a vertical section through the device;

Fig. 2 is a side elevation of the water inlet, and automatic control means for the same, a portion of the stand pipe being 65 shown in section;

Fig. 3 is a side elevation of the overflow pipe that is connected with the liquid containing chamber;

Fig. 4 is a vertical section through the 70 damper control apparatus;

Fig. 5 is a detailed transverse section through the smoke duct, and

Fig. 6 is a detailed transverse section 75 through the agitators and baffles that are disposed in the liquid container or chamber.

In describing my invention I shall refer to the drawings in which similar reference characters designate corresponding parts throughout the several views. The device 80 consists primarily of a liquid containing chamber 1, which has one end thereof connected with a smoke flue or chimney 2, said flue being provided with automatically controlled draft regulators 3, which will be 85 hereinafter described more specifically. The container or chamber 1 is divided into two parts, the inlet portion being designated by the numeral 4, and inclined, while the other portion 5 thereof is disposed vertically, 90 and is provided with a main outlet 6 in the top thereof. Disposed adjacent the inlet of the liquid container, and communicating with the smoke flue 2 is a by-pass 7, which extends upwardly, and is connected with the 95 outlet 6 of said body. This by-pass is controlled by a pair of flap valves 8, which are adapted to either cut off the purifying chamber, or the by-pass, as desired, so as to direct the smoke through either one or the other. 100

The liquid containing chamber 1 is adapted to be filled with water to a predetermined level, and projecting in through the portion 4 of said chamber are a plurality of parallel disposed smoke ducts 9, which have their 105 upper ends contracted as shown at 10, and communicating with the outer end of said portion, and with the smoke flue 2. Positioned in the portion 10 of the ducts, are a pair of fans, which are driven by a motor, 110 or any other desired means, one fan being designated by the numeral 11 comprising the

main fan, and a smaller fan 12 being designated the relay fan, for forcing the smoke from the flue through the ducts and into the chamber 1. This construction will create a 5 submerged draft, so that the smoke drawn from the flue will be driven through the ducts, the ducts being surrounded by the liquid, which acts as a cooling agent therefor, and as the lower inner ends of said ducts 10 terminate adjacent the bottom of the chamber 1, the smoke will be projected or driven therefrom within the liquid. The terminal ends of the ducts 9 are curved slightly upwardly and they are adapted to direct the 15 smoke discharged therefrom into contact with the primary purifying means.

This primary purifying means comprises a plurality of vertically spaced rows of agitators, which are formed of disks 13 mounted on a horizontally extending axis 14, said disks having a plurality of teeth 15 in the peripheral edges thereof, and the axis on which the disks are mounted being revolvable, by means of a motor, or any other drive 25 mechanism connected therewith, so that the disks will be continually rotated to agitate the water for a purpose which will be hereinafter more fully described. Spaced between the disks 13 are diagonally arranged 30 baffles 16 which extend inwardly from the opposite sides of the portion 5 of the liquid container. These sets of agitators and baffles are disposed within the portion 5 of said container beneath the water level, and 35 arranged in the top of the chamber above the water level, and in the outlet 6 are additional inwardly projecting inclined baffles 17 which will supplement the primary action of the baffles and agitators that are 40 submerged within the chamber.

The bottom of the liquid containing chamber 1 is provided with spaced outlet and inlet openings, one of which is designated by the numeral 18, and the outlet opening is 45 connected with a stand pipe 19, by a short length pipe 20, as clearly shown in Fig. 3 of the drawings, the said overflow being carried through the pipe 20 and up the stand pipe 19, flowing over the upper edge thereof 50 and being caught in a basin 21 over which said pipe is positioned. The lower end of the pipe 19 is provided with a valve 22, which is normally slightly open, and which is adapted to catch the solid products of 55 combustion that are carried by the liquid from the bottom of the chamber 1.

To maintain a constant water level within the chamber 1 I have provided an automatically controlled water inlet means, 60 which includes a connection 23 which extends through the inlet opening 18 in the bottom of the container 1, said connection being connected with a supply pipe 24, having a valve 25 therein. This valve 25 is a 65 slide valve and carries a stem 26 extending

upwardly therethrough and having a fulcrumed arm 27 connected therewith on its upper end. The inlet 23 of the pipe 24 is also connected with a stand pipe 28, and positioned within said stand pipe is a float 29 connected with the cable which is trained over a pair of pulleys 30 in the upper end of said stand pipe and secured to one end of the fulcrumed arm 27 on the upper end of the valve stem 26. This end of the arm 75 is also provided with a counterbalancing weight 31, and it is obvious that upon the operation of this construction the valve 26 will be automatically operated to control the same, and hence the flow of liquid to 80 the container 1. The water level within the stand pipe 28 is approximately the water level within the chamber, said stand pipe being disposed adjacent one side thereof. It is obvious that upon the water level in 85 the chamber being lowered the water will be lowered in the pipe 28, and the float will drop therein, and raise the arm 27, hence lifting the valve and allowing more water to flow through the pipe 24 and pipe 23 to 90 the container or chamber 1. When the predetermined water level has been reached, the valve will be once more automatically closed, by the float lifting within the stand pipe, and the weight 31 pulling the arm 27 downwardly, and hence closing the valve. 95

The smoke flue 2 is provided with a pair of diametrically positioned draft controlled inlets 3, said inlets being formed with beveled walls, that are positioned in openings 100 in the wall of said flue, that are likewise beveled, as clearly shown in Fig. 4 of the drawings. The draft controlling devices 3 which act as closures are hingedly connected with the wall of the flue, as shown at 32, 105 and the same are adapted to swing inwardly, they however being normally closed by means of a support 33 secured to the outer face thereof, and having a weight 34 carried thereby. To limit the inward swinging 110 movement of the closure 3 a projecting arm 35 on the inner surface thereof is provided having an eye 36 on its outer end adapted to slide on a hinged rod 37 secured to the inner wall of said flue. The rod 37 has a 115 head 38 on its outer end, to limit the inwardly swinging movement of said closure. These draft devices will be automatically operated, when the draft is sufficient to draw them inwardly by lifting the weight 34. As 120 soon as released, the weight 34 will automatically swing them back to closed position.

In operation, when the valves 8 are so positioned, as to close the by-pass 7, smoke 125 from the flue 2 will be directed into the chamber 1. This smoke is drawn into the smoke ducts 9 by means of the fans 11 and 12, and as the same passes through the parallel arranged ducts, which form separate 130

passages, within the portion 4 of said chamber, the liquid of the chamber will act as a cooling agent, and as the smoke is discharged from the inner ends of said ducts 5 adjacent the bottom of the chamber 1, the heavier particles will be deposited in the bottom of the chamber. The smaller particles consisting of minute solid particles or products of combustion will be carried upwardly through the portion 5 of the chamber 10 through the liquid in small globules, and to break up the same the agitators and baffles submerged within the liquid are employed. This will cause the minute particles or solid products of combustion to be deposited or precipitated in the bottom of the chamber 1, while the gaseous products of combustion will pass upwardly through the chamber, and out the outlet 6. The baffles 15 will supplement the action of the agitators and baffles that are submerged within the portion 5 of the chamber. By this means the smoke will be purified, and all the solid and valuable products will be 20 precipitated in the bottom of the chamber 1.

The overflow attachment to the chamber 1, will carry the solid products of combustion through the outlet, and hence in a manner hereinbefore fully described the same will 25 be carried to a basin, which receives the same, and hence they may be transported to any desired place. Owing to the fact that the liquid is constantly flowing from the chamber 1, carrying the solid products of combustion therefrom, the chamber is provided 30 with an automatic liquid inlet, which maintains a predetermined water level constantly therein. The smoke flue is provided with automatically controlled draft regulators, the operation of which has been hereinbefore fully described. The by-pass 7 allows the purifying device to be cut off, upon 35 operation of the valves 8, when it is desired to clean the interior of the same. The portion 5 is provided with a door, designated by the numeral 39, whereby access to the interior of the chamber may be easily obtained. The spaced rows of agitators that are submerged in the portion 5 of the chamber 1 40 are adapted to rotate in opposite directions, that is the upper and lower rows or disks agitating in one direction, while the center row agitates oppositely therefrom. This will thoroughly agitate the water, to accomplish 45 the desired purpose. The various parts used in this apparatus are formed of suitable material, so that they will not corrode or wear under the action of the gases that pass therethrough.

50 The operation of this type of smoke purifier will obviate the smoke nuisance, and enables bituminous coals to be used in various kinds of furnaces, for instance smelting fur-

naces, in municipalities where anti-smoke laws are in force. The purifying apparatus 55 also retrieves the valuable solid products of combustion that were heretofore carried off by the gaseous products and wasted.

From the foregoing description, taken in connection with the accompanying drawings, 70 the advantages of the construction and the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claims appended hereto.

Having fully described my invention, what I claim as new, and desire to secure by Letters Patent, is:

1. In a smoke purifier the combination with a liquid containing chamber, a smoke duct terminating adjacent the bottom thereof, means for forcing smoke through said duct, an outlet in the top of said chamber, 90 parallel vertically spaced rows of agitators and baffles in said chamber adjacent the terminal of the smoke duct, and supplemental baffles in said chamber above the liquid level and adjacent the outlet. 95

2. In a smoke purifier the combination with a liquid containing chamber, a smoke duct terminating adjacent the bottom thereof, means for forcing smoke through said duct, agitators and baffles in said chamber 100 adjacent the terminal of the smoke duct, and a liquid outlet and inlet in the bottom of said chamber to draw the precipitation therefrom and maintain the liquid level in said chamber. 105

3. In a smoke purifier the combination with a liquid containing chamber, agitators and baffles in said chamber, a smoke duct comprising a plurality of parallel passages terminating adjacent the bottom of said 110 chamber, said passages having their upper ends connected and communicating with the smoke flue, and a pair of draft fans disposed therein.

4. In a smoke purifier, the combination with a liquid containing chamber, a smoke duct terminating adjacent the bottom thereof, means for forcing smoke through said duct, an outlet in the top of said chamber, and parallel vertically spaced rows of agitators and baffles in said chamber below the liquid level and adjacent said outlet. 120

In testimony whereof, I affix my signature hereto.

WILLIAM L. BOYD.
